Attorney.

UNITED STATES PATENT OFFICE.

JOHN H. IRWIN, OF MORTON, PENNSYLVANIA.

PORTABLE ELECTRIC LAMP.

SPECIFICATION forming part of Letters Patent No. 429,172, dated June 3, 1890.

Application filed June 30, 1881. Serial No. 38,844. (No model.)

To all whom it may concern:

Be it known that I, JOHN H. IRWIN, of Morton, in the county of Delaware and State of Pennsylvania, have invented certain new and useful Improvements in Portable Electric Lamps, of which the following is a full, clear, and exact description, reference being had to the accompanying drawing and the letters marked thereon.

My invention consists in the application of electricity for illumination to a portable lamp, and consists, essentially, in combining in one and the same organization an electric lamp and a secondary battery, as hereinafter described.

The method of arrangement and construction of the constituent parts of the device is such as to render the same compact and light as possible, and to attain this end I employ what is known as the Planté or Faure secondary battery in connection with my improved incandescent lamp, locating said battery in the base of the structure.

In constructing the secondary battery I employ lead rolled very thin in order to expose as much surface as possible and to render the device light and easy to handle, and also use a small incandescent lamp in order to admit of the construction of a completed device of such weight as to be easily moved from place to place at the pleasure of the person using it; and my invention involves certain novel and useful arrangement of parts and peculiarities of construction and operation, all of which will be hereinafter first fully described, and then pointed out in the claim.

In the drawing the figure is an elevation and partial section showing the simplest form of construction of my improved portable lamp and the arrangement of the interior parts.

A is the base and side wall or shell of the battery-holder of the lamp. It may be constructed of hard rubber or any other preferred light non-conducting material, and may be ornamented in any pleasing manner.

B is a battery-cup, composed of thin glass, fitting nicely into the shell A. It is made very light in order not to add materially to the weight of the structure.

C is the lead roll, &c., (the same being cut in section in order to show the convolutions

in the figure,) composing the secondary battery, the same being constructed in the well-known manner employed by those skilled in the art to which my improvement relates. 55

The battery may be of the Planté or Faure type; or, if desired, a dry battery may be used, the latter being preferable when the lamp is to be subjected to considerable motion.

A' is a disk of suitable material fitting into 60 the base of the lamp and secured thereto by means of screw-threads upon its periphery or in any other preferred manner, the same being so arranged as to support the battery-cup when placed within the shell. 65

A² is a cover or top for the battery-casing. The same is so arranged as to be easily removed, when necessary, in order to reach the inclosed battery.

Mounted upon the cover A² is placed a standard D, supporting the lamp and its adjuncts upon its upper extremity. Shaft D may be hollow for the purpose of inclosing the connections between the battery and lamp, as shown. 75

The lamp L represented in the drawing is that fully described in another application for Letters Patent made by me. It should be of small size, giving when in operation a light equal to that usually obtained from an ordinary four-foot gas-burner. By using a lamp of this power I am enabled to construct my battery small and light enough to permit easy removal from place to place wherever the light is required. 85

An insulated wire a forms the connection between one pole of the battery and lamp and a binding-post E upon casing A. a' is the connection with the other pole of the lamp, terminating at switch-connection a². F is a 90 switch having connection with the other pole of the battery. Binding-post E' has connection with switch-point a³, as shown.

In charging the battery the poles G G of a dynamo-electric machine are connected to the 95 binding-posts E E'. By turning the switch to the right connection is made between one pole of the battery and a³, throwing the lamp out of circuit and establishing electrical connection with the dynamo-machine. When the 100 battery is sufficiently charged, the switch is turned to a point between a² and a³, as shown

in the figure, and the dynamo-connections removed.

In starting the lamp connection is made between the switch and α^2 , completing the circuit of the battery through the lamp.

Having now fully described my invention, what I claim as new therein, and desire to secure by Letters Patent, is—

The combination of a closed base, a secondary battery located within said base, a hollow standard extending up from said base and provided at its upper end with a lamp-holder,

an electric lamp supported by said holder, and conducting-wires connecting said secondary battery and lamp, for the purpose set forth, substantially as described.

In testimony that I claim the foregoing I have hereunto set my hand in the presence of two witnesses.

JOHN H. IRWIN.
